UNITED STATES PATENT OFFICE.

ALBERT D. WOOD, LAWSON TRANTHAM, AND EDWARD T. SELF, OF CANTON, NORTH CAROLINA.

PULP-WOOD BREAKER.

1,414,914.

Specification of Letters Patent. Patented May 2, 1922.

Application filed September 17, 1920. Serial No. 410,966.

To all whom it may concern:

Be it known that we, ALBERT D. WOOD, LAWSON TRANTHAM, and EDWARD T. SELF, citizens of the United States, residing at 5 Canton, in the county of Haywood and State of North Carolina, have invented certain new and useful Improvements in a Pulp-Wood Breaker; and we do hereby declare the following to be a full, clear, and exact 10 description of the invention, such as will enable others skilled in the art to which it appertains to make and use the same.

An object of the invention is to provide means in connection with a wood chipping machine employed for preparing pulp wood to be subjected to the digesting step in the process of preparing pulp in the manufacture of paper, whereby the chips as they are detached from the block or log by the chipping 15 per and many of which are too large to be properly and effectively submitted to the digesting operation, may be broken up or reduced to a suitable size, without involving the crushing and pulverizing of the same or 20 portions thereof as in accordance with the ordinary methods of treatment and which involve considerable amount of waste due to the fact that the dust or fine particles and the splinters must be screened out and discarded 25 in favor of the portions containing fibres of the required lengths. In accordance with the usual procedure the products of the chipper or of the chipping machine which serves to detach the required length 30 of wood by diagonal or oblique cuts from the logs or blocks are sorted, those of the proper size being subjected immediately to the digesting operation and those of a size exceeding that which can properly be treated 35 in the digester being subjected to an intermediate treatment as of crushing or grinding, with the result that there is a considerable percentage of waste caused by the production of fine dust and splinters which as 40 above noted must be screened out, and taking advantage of the fact that as the chips leave the chipper head after being detached from the blocks or logs they are projected with considerable force at an angle to and in 45 a direction substantially perpendicular to the plane of the chipper head, it is the object of this invention to dispose in the path thereof a structure which will operate to break up those chips which exceed a prede-

termined size, to the end that after the completion of the chipping operation all of the products of the chipping mechanism may be deposited at once in the digester with a minimum amount or percentage of screenings incident only to the operation of the chipping knives; and furthermore to provide means for the purpose indicated which may be readily applied to and used in connection with chipping machines or mechanisms of the type now ordinarily employed and at a minimum cost both for installation 65 and maintenance.

Further objects and advantages will appear in the following description of a preferred embodiment of the same, it being understood that changes in form and proportions may be resorted to within the scope of the appended claims, without departing from the principles involved.

In the drawings:

Figure 1 is a plan view of the breaker mechanism applied in the operative position to a chipping machine.

Figure 2 is a side view of the same.

Figure 3 is a face view of the chipper head or disk showing in dotted lines the location of the breaker head in rear thereof.

Figure 4 is a detail sectional view of a portion of the breaker head showing the means whereby the pins are mounted therein.

Figure 5 is a sectional view of the clutch between the motor and the shaft 17, taken on the line 5—5 of Figure 2.

In the disclosure of a breaker embodying the invention and which consists essentially of a breaker head 10 provided with spurs, prongs, teeth or pins 11, it is shown in operative relation with a chipper of typical form consisting of a revoluble disk 12 having at suitable intervals openings 13 adjacent to which are arranged the chipping blades or knives 14 for successive action upon blocks or logs presented to the disk through a feed spout 15 disposed diagonally or at an inclination with reference to the plane of the disk, and in the operation of this chipping apparatus the blocks or logs fed to the disk are cut upon oblique lines to produce a series of diagonally grained chips or cards which, by reason of the resistance offered to the knives and the power with which the disk is rotated are thrown or cast

or projected in paths substantially perpendicular to the plane of the disk and are usually obstructed in their flight and directed to a suitable place of deposit by means of 5 a bonnet or hood 16 which ordinarily serves to substantially encase or house the disk but which when employed in connection with the breaker forming the subject of this invention may be interrupted as indicated to 10 provide for the disposition of the head of the breaker in the path of the chips as they leave the chipping knives. As is well known to those familiar with this art there is a considerable percentage of the chips as 15 they are detached from the logs or blocks which are of a suitable size to be subjected at once or without further manipulation or treatment to the digesting step of the process, but at the same time there is a considerable 20 percentage of larger chips known generally as cards, which are of a size not adapted to be subjected to the digesting operation under the most favorable condition and which therefore must be reduced, 25 and by disposing the spurred or pronged breaker head in the path of movement of the chips and cards as they leave the chipper head or disk, the said spurs or prongs of which are sharpened or reduced at their 30 extremities substantially in the line of flight of the chips or cards, the latter are thrown forcibly against the ends of the spurs or prongs and are thus further divided, those larger chips known as cards particularly 35 being subjected to this breaking operation which serves to reduce the product from the chipper to a substantially uniform size, or at least a size which is suitable for digesting. The prongs or spurs or pointed projections 40 on the breaker head are located at intervals such as to insure the engagement of the cards or larger chips with the extremities of one or more of these projecting elements, and the force with which the chips encounter 45 the ends of the spurs or prongs is sufficient to cause the splitting or breaking thereof without reducing the same to splinters or dust.

The rotary motion of the chipper head by 50 reason of its centrifugal action has a tendency to cause a tangential movement to the chips in addition to the movement thereof in a path substantially perpendicular to the plane of the chipper head, and therefore 55 with a view to increasing the efficiency of the breaker it is preferable to dispose the breaker head slightly outward of the vertical plane of the feed spout, and to rotate said breaker head rapidly so as to minimize 60 the tendency of the chips and particularly of the larger chips or cards by reason of approaching the breaker head in an endwise position passing between the teeth or prongs and contacting with the breaker head without 65 impalement upon the ends of the teeth,

and such rotary motion may be imparted to the breaker head by mounting it through the agency of a shaft 17 in suitable bearings 18 supported by the chipping machine as indicated in Figures 1 and 2 and connecting 70 said shaft with a motor 19 as of the electrical type, said breaker head being driven preferably at a high rate of speed which however may be modified with relation to and at such a ratio regarding that of the 75 chipper head, as to secure the desired result, namely of causing the proper movement without an excessive reduction of the chips as they leave the chipper head. Obviously the extent of reduction of the chips will be in 80 a degree proportionate to the speed at which the breaker head is driven with relation to that of the chipper head, but in practice it is found that with even the breaker head stationary, the larger proportion of the cards 85 will be divided or reduced sufficiently for immediate subjection to the digesting operation.

In practice it is preferred to employ a relatively heavy disk as a head of the 90 breaker, provided with transverse openings or seats 18' at suitable intervals, and to provide the terminally reduced pins, which are preferably angular in cross section, so as to present angles for contact with the cards or 95 chips, with a shoulder 19' to bear against the surface of the disk, the reduced stem 20 extending through said seats or sockets and being engaged at the opposite surface of the head by nuts 21 or equivalent fastening 100 means. Obviously broken or dulled pins may readily be replaced and the degree of reduction or sharpness of the pins and the corresponding sharpness of the angles thereof may be varied to insure the most efficient 105 action upon the chips as they are forcibly discharged against the breaker head by the action of the chipper mechanism.

Having thus described the invention, what we claim is:—

1. The combination with a chipper head of a pronged breaker head having chip impaling means disposed in the path of chips projected from the former.

2. The combination with a chipper head 115 of a rotary pronged breaker head having chip impaling means disposed in the path of the chips projected from the former.

3. The combination with a chipper head of a breaker head having chip impaling 120 means disposed in the path of chips projected from the chipper head and consisting of forwardly extending terminally reduced prongs or pins.

4. The combination with a chipper head 125 of a breaker head having chip impaling means arranged in the path of chips projected from the chipper head and consisting of forwardly extending terminally reduced pins or prongs having lateral angles. 130

5. The combination with a rotary chipper head, of a breaker head having chip impaling means disposed in the path of tangential flight of chips from the chipper head and
5 provided with forwardly extending cross sectionally angular and terminally reduced pins or prongs, and means for rotating the breaker head.

6. The combination with a chipping means
10 of chip splitting means consisting of ele-

ments arranged to impale chips in their flight from the chipping means.

In testimony whereof we affix our signatures in presence of two witnesses.
